DESIGN FOR A CAP

Arthur W. Dahlquist, San Francisco, Calif.

Application October 28, 1933, Serial No. 49,581

Term of patent 7 years

To all whom it may concern:

Be it known that I, ARTHUR W. DAHLQUIST, a citizen of the United States of America, residing at San Francisco, in the county of San Francisco and State of California, have invented a new, original, and ornamental Design for Caps, of which the following is a specification, reference being had to the accompanying drawing, forming a part thereof.

Fig. 1 is a front elevational view, slightly in perspective, of a cap showing my design; and

Fig. 2 is a side elevational view, slightly in perspective, of the same.

I claim:—

The ornamental design for a cap substantially as shown.

ARTHUR W. DAHLQUIST.
